UNITED STATES PATENT OFFICE

127,155

DESIGN FOR A RADIO-PHONOGRAPH CABINET

Emil I. Harman, Philadelphia, Pa., assignor to
Philco Radio and Television Corporation,
Philadelphia, Pa., a corporation of Delaware

Application January 31, 1941, Serial No. 98,623

Term of patent 14 years

To all whom it may concern:

Be it known that I, Emil I. Harman, a citizen of the United States, residing in Philadelphia, Philadelphia County, Pennsylvania, have invented a new, original, and ornamental Design for a Radio-Phonograph Cabinet, of which the following is a specification, reference being had to the accompanying drawings, forming part thereof, in which:

Fig. 1 is a perspective view of a radio-phonograph cabinet showing my design; and

Fig. 2 is a different perspective view of the cabinet as it appears in open condition for access to the phonograph.

I claim:

The ornamental design for a radio-phonograph cabinet, substantially as shown.

EMIL I. HARMAN.
